(57) **CLAIM**

The ornamental design for a disposable noise-resistant and shielded electrode, as shown and described.

DESCRIPTION

FIG. 1 is a front perspective view of a first embodiment of the disposable noise-resistant and shielded electrode showing the design;

FIG. 2 is a rear perspective view thereof;

FIG. 3 is a front elevational view thereof;

FIG. 4 is a rear elevational view thereof;

FIG. 5 is a right side view thereof;

FIG. 6 is a left side view thereof;

FIG. 7 is a front perspective view of a second embodiment of the disposable noise-resistant and shielded electrode showing the design;

FIG. 8 is a rear perspective view thereof;

FIG. 9 is a front elevational view thereof;

FIG. 10 is a rear elevational view thereof;

FIG. 11 is a right side view thereof; and,

FIG. 12 is a left side view thereof.
